 Claims priority, application Australia Jan. 26, 1962
 9 Claims. (Cl. 340—282)

This invention relates to a slalom course used in the sport of water skiing comprising a zig zag course of uniform pitch and amplitude, marked out on the water by a buoy at each turning point. The boat towing the skier travels in a straight line midway between the buoys and the skier attempts to follow the zig zag course passing around the outside of each buoy.

At present all slalom courses are marked by two rows of aligning buoys floating on the surface of the water and anchored in position, and between which rows the towing boat is centrally driven. Considerable time is required to lay out the slalom course in this manner, which course cannot be left set up in public waters because of the hazard it represents to other boats when not in use and particularly at night. It is thus difficult for skiers to learn and practice slalom skiing except on the few permanent courses provided on private waterways.

It is therefore the principal object of the present invention to provide an apparatus for indicating the turning points of a slalom course to a water skier, which apparatus can be operated from the towing boat, does not interfere with other boats in the area, and is effective and accurate in operation.

With the above stated principal object in view there is provided according to the present invention for indicating the turning points of a slalom course to a water skier being towed by a boat, an apparatus comprising signal means to indicate to the skier that he is alternately located a distance on either side of the line of travel of the boat corresponding to the lateral spacing of the turning points from said line of travel, and intermittent signal means to indicate to the skier regular time intervals corresponding to the time allowed to travel the longitudinal distance between the turning points commensurate with a predetermined boat speed, whereby the skier can by co-ordinating the two signal indications, determine the turning points whilst traversing the slalom course.

More specifically there is provided audible or visible signal means operable in response to movement of the ski rope to issue a signal when the skier is located a lateral distance from the line of travel of the boat corresponding to the lateral spacing of the turning points from said line of travel, and audible or visible signal means arranged to issue a signal to the skier at predetermined regular time intervals corresponding to the time required to travel the longitudinal distance between the turning points, whereby co-ordination by the skier of the two signals will indicate the turning points of the slalom course whilst travelling therethrough.

Conveniently each signal means comprises a light mounted in the boat to direct a beam of light rearwardly towards the skier, each light being of a different color. One light flashes at regular intervals, the interval being set to correspond to the time available to travel the longitudinal distance between the turning points at any selected boat speed. The other signal light is controlled by a switch actuated by the skier's tow rope when the rope is inclined at a predetermined angle to, and on either side of, the line of travel of the boat along the center line of the course. The angle at which the switch is actuated is determined by the lateral spacing of the turning points and the length of the rope. Under championship skiing rules in regard to the length of the ski-rope

and the spacing of the turning points from the line of travel of the boat the angle is 30°.

The provision of these two lights enables the skier to know when he is offset or displaced the correct lateral distance from the line of travel of the boat and if he is arriving at this point within the time allowed by the spacing of the buoys of a standard slalom course and the speed of the boat.

The invention will be more readily understood from 10 the following description of one practical arrangement of the apparatus with reference to the accompanying drawings.

In the drawings:

FIG. 1 is a diagrammatic layout of a slalom water ski 15 course in accordance with the prevailing international rules for championship water skiing.

FIG. 2 is a plan view of the apparatus.

FIG. 3 is an elevation of the apparatus.

FIG. 4 is a sectional view along line 4—4 in FIG. 3.

FIG. 5 is a detailed view of the ski rope clip taken in the direction 5—5 in FIG. 3, and

FIG. 6 is a schematic diagram of the electrical circuit of the apparatus.

Referring now to FIG. 1, in a championship water ski 25 slalom course the turning points normally indicated by the buoys 10 are located twelve and one half yards on either side of the center line 11 of the course, and the longitudinal distance between successive turning points, which are located on opposite sides of the center line of the course, is forty five yards. The ski rope 12 by which the skier is towed through the course by the boat 13 is twenty five yards long, and thus when the skier is rounding one of the buoys the angle α that the ski rope makes with the line of travel of the boat is 30°. In completion 35 of the skier is towed through the course a number of times until he fails to negotiate one of the buoys marking the turning points. The speed of the boat is increased in steps of 2 m.p.h. on each successive pass through the course, the first pass being made at 24 m.p.h.

40 In order to simplify the following description of the apparatus we shall assume that the apparatus is adjusted to indicate the turning points of the above described championship slalom course when the boat is travelling at 30 m.p.h.

45 The apparatus comprises a housing 15 mounted upon the upper end of a conventional ski-pole 16 secured to the boat. The rear section of the housing is made up of two lamp lines 17 and 18 colored red and orange respectively. Electric globes RL and OL are located behind 50 the respective lens and are energized as hereinafter described so that the longitudinal spacing of the turning points is indicated by a red light and the lateral spacing by an orange light.

Mounted in the housing 15 is the micro switch 20 55 which controls the flow of current from the battery B to the globe OL behind the orange lens (FIG. 5). The switch 20 is pivotally connected to the base of the housing 15 by the screw 21. The adjusting screw 22 is in threaded engagement with the nut 23 secured in the side wall 24 of the housing and an inner tapered end 25 of the screw engages the projection 26 on the micro switch 20 to permit adjustment of the position of actuating roller 27 of the switch relative to the cam 30.

60 The cam 30 is attached to the shaft 31 which is journaled in and projects downwardly through the base of the housing. The actuating arm 32 is attached to the lower end of the shaft 31 and carries at the rear most end a rope clip 33. The clip comprises two resilient legs 34 joined at the upper end and abutting each other at the lower end 36 to form an elongated loop through which the ski rope 12 passes. If the ski rope becomes entangled in the propeller of the boat or some other sub-

merged object the downward pull on the rope will automatically free the rope from the clip and prevent damage to the apparatus.

The ski rope is attached to the hook 49 on the ski-pole 16 which is forward of the rope clip 33 and thus, as the skier moves laterally outwards from the line of travel of the boat, the actuating arm 32 will effect a partial rotation of the shaft 31 and cam 30. The contour of the cam and the relative disposition of the switch is arranged so that upon the ski rope attaining an inclination of 30° to the line of travel of the boat, on either side thereof, the switch 20 will close and energize the globe OL so as to show an orange light to the skier. As previously explained this angular disposition of the ski-rope corresponds to the skier being laterally displaced from the line of travel of the boat a distance corresponding to the lateral spacing of the turning points of the slalom course.

In order to indicate to the skier the longitudinal spacing of the turning points of the slalom course the globe RL behind the red lens 17 is connected to the battery B by any one of the known automatic flashing circuits FC which will effect a regular flashing of the globe RL. The flashing circuit includes a control which permits variation of the time which elapses between each flash of the globe RL so that this time can be set to suit different boat speeds, e.g. when the boat is travelling at 30 m.p.h. it will take approximately 3 seconds for the boat to travel the 45 yards between successive turning points in the course and thus the globe RL would flash at 3 seconds intervals.

With the energization of the two globes OL and RL controlled in this manner the skier can ascertain from the orange light when he has moved a sufficient distance laterally from the line of travel of the boat to pass around the turning point of the slalom course, and the regularly flashing red light indicates if this position is reached with the time available in accordance with the longitudinal spacing of the turning point and the particular speed of the boat. The skier is on course if the orange light flashes before or at the same time as the red light flashes, but if the red light flashes first it indicates that the skier is travelling too slow to reach the turning point within the available time.

If desired the circuit of the orange light can be interconnected to the automatic flashing circuit of the red light so that if the orange light is energized before the red light has flashed then the approaching flash of the red light will be cancelled and the flashing circuit will immediately commence to measure the period for the next flash of the red light. In this manner whilst the skier continues to travel at sufficient speed to achieve the required lateral displacement within the time allowed he will only see flashes from the orange light. The red light will only flash when the skier fails to reach the lateral displacement within the allowed time.

In another modification of the apparatus the red light indicating the longitudinal spacing of the turning points may be arranged to flash at each turning point in the course and also at a point midway between the successive turning points. This intermediate flash of the red light would correspond to the time when the skier should be crossing the line of travel of the boat between each turning point, and thus indicates to the skier whether he is on course or whether he must increase his speed in order to reach the next turning point on time.

In the foregoing description reference has been made to the dimensions of a championship slalom course, however the apparatus according to the present invention can be used to produce a course of any desired dimensions and is particularly advantageous for learner skiers as the course can be set initially to make completion of it simple and then adjusted gradually up to championship conditions as the skiers' ability improves.

It will also be realised that the automatic flashing circuit controlling the red light which indicates the longitudinal spacing of the turning points can be set to indi-

cate this spacing at any boat speed independent of the actual speed of the boat, i.e. for a speed faster, slower or equal to the actual boat speed. In this manner a learner skier can practice at a slalom speed of 15 m.p.h., behind a boat travelling at 25 m.p.h. and an expert skier can practice at a slalom speed of 40 m.p.h. with a boat travelling at a speed of 32 m.p.h. This arrangement allows the learner skier more time to reach the turning points and yet the boat can travel at a sufficiently fast speed to provide adequate lift to the ski by the water, and permits the expert skier to practice at a slalom speed higher than the maximum speed attainable by the boat.

Although the apparatus described herein has incorporated different colored lights as the signal means it is to be understood that horns or other electrically operated audio devices of different tones may be used to replace, or in combination with the lights.

I claim:

1. For indicating the turning points of a slalom course to a water skier being towed by a boat, an apparatus comprising signal means to indicate to the skier that he is alternately located a distance on either side of the line of travel of the boat corresponding to the lateral spacing of the turning points from said line of travel, and intermittent signal means to indicate to the skier regular time intervals corresponding to the time allowed to travel the longitudinal distance between the turning points commensurate with a predetermined boat speed, whereby the skier can by co-ordinating the two signal indications, determine the turning points whilst traversing the slalom course.

2. For indicating the turning points of a slalom course to a water skier being towed by a boat, an apparatus comprising audible or visible signal means operable in response to movement of the ski rope to issue a signal to the skier that he is alternately located a lateral distance from and on either side of the line of travel of the boat corresponding to the lateral spacing of the turning points from said line of travel, and audible or visible signal means arranged to issue an intermittent signal to the skier at regular time intervals corresponding to the time allowed to travel the longitudinal distance between the turning points commensurate with a predetermined boat speed, whereby co-ordination by the skier of the two signals whilst traversing the slalom course will indicate the turning points thereof.

3. An apparatus for fitment to a boat to indicate the turning points of a slalom course to a water skier being towed by a ski rope attached to the boat comprising lateral signal means operable by the ski rope upon the latter attaining a predetermined inclination to and on either side of the line of travel of the boat to indicate to the skier that he is laterally displaced from the line of travel of the boat a distance equal to the lateral spacing of the turning points from said line of travel, and longitudinal signal means constructed and arranged to emit an intermittent signal at regular time intervals corresponding to the time allowed to travel the longitudinal distance between the turning points commensurate with a predetermined boat speed, whereby co-ordination by the skier of the two signals whilst traversing the slalom course will indicate the turning points of the course.

4. An apparatus as claimed in claim 3, wherein the lateral and longitudinal signal means comprise separate light sources arranged to direct beams of light of different colors towards the skier.

5. An apparatus as claimed in claim 3, wherein the lateral signal means comprises a colored light source, an electrical power supply to energize said light source, a switch to selectively connect said power supply to said light source and a cam actuated in response to the relative movement between the ski-rope and the boat as the skier moves in a lateral direction relative to the line of travel of the boat, said cam being arranged to operate the switch and energize the light source when the ski

rope attains the predetermined inclination to and on either side of the line of travel of the boat.

6. An apparatus as claimed in claim 5, wherein the longitudinal signal means comprises a different colored light source, a flashing control circuit connecting said different colored light source to said electrical power supply and constructed and arranged to energize said different colored light source at regular intervals so as to emit an intermittent flash, and means within said circuit to adjust the period of said intervals to correspond to the time allowed to travel the longitudinal distance between the turning points in accordance with the boat speed.

7. An apparatus for fitment to a boat to indicate the turning points of a slalom course to a water skier being towed by a ski-rope attached to said boat comprising a housing adapted for attachment to the boat, two light compartments forming at least part of the rear of said housing, an electric light globe mounted in each light compartment, a translucent portion in each light compartment constructed and arranged so that beams of different colored light are directed towards the skier when the respective globes are energized, an electrical power supply to energize said globes, a switch mounted in the housing to selectively connect one of the globes to said power supply, a cam mounted in said housing for relative angular movement, an actuating arm connected to said cam and disposed externally of that housing, said actuating arm being adapted for coupling to the ski-rope so as to effect angular movement of the cam as the ski-rope adopts an inclination to the line of travel of the boat, the cam

being shaped and arranged relative to the switch to actuate the latter and flash said one of the globes upon the ski-rope attaining a predetermined inclination to and on either side of the line of travel of the boat corresponding to the skier being located a lateral distance from said line of travel equivalent to the lateral spacing of the turning points of the course, a flashing control circuit connecting the other globe to the electric power supply and arranged to energize said other globe at regular intervals, and control means in said circuit to adjust the period of said intervals to correspond to the time allowed to travel the longitudinal distance between the turning points in accordance with the boat speed, whereby the skier can ascertain the turning points of the slalom course by co-ordinating the flashes from the respective globes.

8. An apparatus as claimed in claim 7, wherein the flashing control circuit is interconnected with the switch and arranged so that if the switch is actuated before the said other globe is flashed the flashing control circuit is reset to commence timing of the interval for the next flash of said other globe.

9. An apparatus as claimed in claim 7, wherein the flashing control circuit is constructed and arranged so that the interval between flashes of the other globe is equal to one half of the time allowed to travel the longitudinal distance between the turning points whereby the alternate flashes indicate when the skier should be crossing the line of travel of the boat.
